UNITED STATES PATENT OFFICE.

BALSER HARR, OF KANSAS CITY, MISSOURI, ASSIGNOR TO CATHERINE HARR, OF KANSAS CITY, MISSOURI,

MOP-MAKING MACHINE.

1,247,675.

Specification of Letters Patent. Patented Nov. 27, 1917.

Application filed July 19, 1915. Serial No. 40,617.

To all whom it may concern:

Be it known that I, BALSER HARR, a citizen of the United States, residing at Kansas City, in the county of Jackson and State of Missouri, have invented certain new and useful Improvements in Mop-Making Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to mop making machines, and more particularly to a machine for making what is commonly known as ferrule mops; the principal object of the invention being to provide means for easily and quickly tying the yarn to a handle plug and applying a ferrule to the plug, so that the ferrule may be attached to a handle to complete the mop.

It is also an object of the invention to provide improved details of structure; the preferred forms of which are illustrated in the accompanying drawings, wherein:

Figure I is a perspective view of a mop making machine constructed according to my invention.

Fig. II is a cross-sectional view of the same.

Fig. III is an enlarged detail view of one of the handle plugs and yarn bales, shown in position in the placing jaw.

Fig. IV is a longitudinal section of a ferrule and its placing barrel, showing a handle plug and ferrule located in the barrel.

Fig. V is a detail perspective view of the ferrule; a part being broken away to show the handle plug and ball in place.

Fig. VI is a detail perspective view of the ferrule placing barrel.

Fig. VII is a detail perspective view of a filler sleeve for the ferrule placing barrel.

Fig. VIII is a detail view of a mop head and part of the handle to which the head is attached by my improved machine.

Referring more in detail to the drawings: 50 1 designates a table which is supported at a suitable height from the floor by legs 2, and comprises a top or platform 3 having a transverse slot 4 opening through one edge.

Pivottally mounted on a pin 6 that extends 55 across the slot 4, at about the transverse

center of the table, are jaws 7-8; the lower arms 9-10 of which extend below the table top and are yieldingly spaced by springs 11-12 that are connected with the table body and yieldingly retain the jaws in open position, so that they may receive a handle plug therebetween as will presently be described.

Also connected with the jaw arms 9-10 are chains 14-14', one of which is adjustably connected with its jaw arm by a hook 15 and with an eye bolt 16 on a foot lever 17 that is pivotally mounted on the table, while the other chain 14' is adjustably connected with the chain 14; the adjustment being provided in order that the jaws may be held open at various widths according to the size of handle plug used therewith.

In order to provide further adjustment I mount the foot lever 17 on a pin 19 that may take into any of several apertures 21 in a standard 22 that comprises part of the table, so that the lever may be mounted at any desired elevation along the standard.

Fixed to the table and extending upwardly therefrom, at the rear of the slot 4, is a standard 24, having apertures 25 therein, and pivotally mounted on a pin 26 that extends through one of the apertures is a lever 27 comprising spaced bars 28-29.

Mounted on a rod 31 that is pivotally mounted in the arms 28-29, and located between the bars, is a ferrule placing barrel 33 comprising a metal shell that is preferably tapered toward its lower end, and a wooden plug or head 35 that fits snugly within the upper end of the shell and has an edge 36 extending over the edge of the shell. The edge 36 of the head 35 is preferably held with a metal band 37 in order to prevent splitting. The rod 31 upon which the barrel is mounted preferably extends loosely through apertures 38 in the barrel below the head. The head 35 carries a latch pin 40 which slides loosely within the head 35 and has a button 41 at its free end for limiting its movement in one direction and a hook 42 at its opposite end for limiting its movement in the other direction and for taking over the edge of the standard 24 in order to hold the lever 27 upright when not in use; and the lever 27 is provided with a latch 44 comprising a pivoted bar having teeth 45 at its front edge adapted for engaging the front edge of the latch

100 105 110

and has a button 41 at its free end for limiting its movement in one direction and a hook 42 at its opposite end for limiting its movement in the other direction and for taking over the edge of the standard 24 in order to hold the lever 27 upright when not in use; and the lever 27 is provided with a latch 44 comprising a pivoted bar having teeth 45 at its front edge adapted for engaging the front edge of the latch

105 110

plate 46 that is secured to the table, so that when the lever is brought down to place a ferrule on the handle plug, the parts may be pressed tightly together and the lever latched to hold the parts in place while they are nailed or otherwise secured together.

The barrel 33 is provided at one side and near its lower end with a slot 48 through which the nail, by which the ferrule is secured to the handle plug, may be driven.

The handle plug heretofore mentioned comprises a wooden plug 50 of such diameter that it will fit snugly within the metal ferrule 51, and the ferrule 51 is of such size that it will fit closely and snugly over the mop handle 52; the ferrule being provided with apertures 53 at one end through which nails may be driven to attach the ferrule to the plugs, and with an aperture 54 at the upper end through which a nail may be driven to attach the ferrule to the mop handle.

The yarn or mop head 55 is held to the ferrule and handle plug by a bail, preferably of spring wire, and U-shaped to form a neck for holding the yarn, and legs for lying along the handle plug within the ferrule; the ends of the legs being inturned to form keepers 57 that lie over the inner end 30 of the plug within the ferrule to anchor the head to the handle plug.

Presuming the parts to be constructed as described, when a mop is to be assembled, the yarn 55 is placed in the neck of a bail 35 56 and a handle plug 50 placed in the upper end of the bail. The bail with the yarn and plug located therein is then placed in the jaws 7-8 and the legs of the bail pinched by the jaws to press the same into the sides 40 of the plug and locate the keepers over the end of the latter. A ferrule is then positioned in the barrel 33, the latch 42 slipped to free the lever 27, and the lever moved downwardly to push the ferrule over the 45 handle plug and clamp the bail legs to the plug.

When the lever has been lowered to the desired position, it is latched by the toothed bar and the parts held together while the operator drives nails through the ferrule and into the handle plug to fix the same together.

When the ferrule has been nailed in place, the lever 27 is released, the jaws 7-8 55 opened, and the ferrule with the contained parts removed from the barrel 33. The handle 52 is then projected into the open end of the ferrule and the parts nailed to-

gether as heretofore suggested. The barrel 33 may be of sufficient diameter to take the 60 largest size of a ferrule, and when a smaller ferrule is to be used a reducing sleeve 58 is placed in the barrel, the sleeve having a slot 59 that may register with the shell slot 48 in order that the nailing may be accomplished through both members.

Having thus described my invention, what I claim as new therein, and desire to secure by Letters-Patent, is:—

1. In a mop making machine, the combination with a jaw, of means for yieldingly retaining the jaw in open position, means for closing the jaw, a lever movable toward and from the jaw, a ferrule holding barrel on said lever adapted for movement over a 75 member held by said jaw and having a slot for exposing a part of said member.

2. In a mop making machine, the combination with a jaw, of means for yieldingly retaining the jaw in open position, means for closing the jaw, a lever movable toward and from the jaw, a ferrule holding barrel on said lever adapted for movement over a 80 member held by said jaw and having a slot for exposing a part of said member, and a 85 latch on said lever for holding the barrel in coöperative relation to the jaw.

3. In a mop making machine, the combination with a table having a slotted top, of a jaw pivotally mounted in the slot in the 90 table top, means for normally holding the jaw open, means for closing the jaw against a ferrule member to hold said member, a 95 lever movable toward and from the jaw, a ferrule holding barrel pivotally mounted on 95 said lever and adapted for moving the ferrule over the member carried by said jaw, and a latch for holding the lever in functional position.

4. In a mop making machine, the combination with a table having a slotted top, of a jaw pivotally mounted in the slot in the table top, means for normally holding the 100 jaw open, means for closing the jaw against a ferrule member to hold said member, a 105 lever movable toward and from the jaw, a ferrule holding barrel pivotally mounted on 105 said lever and adapted for moving the ferrule over the member carried by said jaw, a 110 latch for holding the lever in functional position; the jaw operating mechanism and said lever being adjustable, for the purpose set forth.

In testimony whereof I affix my signature.

BALSER HARR.
